UNITED STATES PATENT OFFICE.

NAPOLEON RAIL, OF LOWELL, MASSACHUSETTS.

AUTOMATIC CUTTING-OFF DEVICE FOR THREAD-WINDERS.

1,328,196.

Specification of Letters Patent. Patented Jan. 13, 1920.

Application filed March 15, 1919. Serial No. 282,976.

To all whom it may concern:

Be it known that I, NAPOLEON RAIL, a citizen of the United States, residing at Lowell, in the county of Middlesex and State of Massachusetts, have invented certain new and useful Improvements in Automatic Cutting-Off Devices for Thread-Winders, of which the following is a specification.

This invention relates to machines for winding thread or yarn on a core which is usually in the form of a tube, particularly of the type wherein a paper tube or cop is used.

It is especially useful for thread winding machines wherein the threads of two or more spools or shuttle bobbins are wound upon a single paper tube at the same time. In such machines, two or more ends of thread are so caught on a revoluble tube, usually carried by a revoluble spindle, that separate bobbins are built up with spaces between.

When such bobbins are wound up to a predetermined point, a stop motion acts to stop the spindle and tube from revolving, after which each tube is removed and cut off between the bobbins by a hand cutter, knife, or other suitable manually operable means.

The particular purpose of this invention is to provide automatic cutting off means which will score or cut the tube between the windings before the stop motion acts so that, when the tube is removed, the separate spools can be broken apart in the factory without further cutting, or can be packed, shipped and broken apart by the user.

In the drawings, Figure 1 is a front elevation showing parts of a thread winding machine of well known type with my attachment, the parts being shown in the starting position and some parts broken away. Fig. 2 is a front elevation similar to Fig. 1, showing the parts in the position for removing the finished bobbins. Fig. 3 is an elevation from the left of Fig. 1. Fig. 4 shows another form of knife. Fig. 5 is a perspective view showing four bobbins wound on a single paper tube, as they appear when removed from the machine. Fig. 6 is an enlarged detail view showing a cutter cutting the tube and the relation of the thread to the bobbin and spout guide. Fig. 7 is a plan, Fig. 8 an elevation from the

right and Fig. 9 an elevation from the left 55 of the thread guide.

In the drawings, V represents the frame of the machine which carries in any suitable well known manner a revoluble spindle B upon which a tube or cop such as A can be 60 placed to receive the yarn or thread T and to act as a core for the bobbins 10, 11, 12, 13, to be formed by winding it up.

Such spindles are usually of the expansion type, being split as at 14 and having 65 an expansion screw 15 which must be loosened to remove a tube and tightened to hold it in place while revolving.

Such machines have a plate D which serves as a carrier for the thread guide C 70 and is so supported by a hanger 1 pivoted to the frame at 4, that it must be pushed back or caused to recede by the thread as it is wound on tube A guided by thread guide C as the bobbins are built up. A suitable 75 weight 2 or spring tends to press the carrier plate and guide up against the spindle or tube.

This carrier plate D usually carries also a stop motion arm 3 and stop screw 5 which 80 operate stop motion mechanism, not shown, when the plate has receded to a predetermined point, by which the spindle and tube are stopped.

The thread guide C is slidable transversely on plate D, being fixed by set screw 37 to a tube 36 which is caused to reciprocate parallel with the spindle whereby the bobbins are built up in a well known manner.

The above parts are all old.

As the spindle revolves very rapidly, the bobbins are rapidly built up and one operator cannot usually handle more than two at a time. When the bobbin is removed after 95 stop motion acts, the operator puts on a new tube, winds four ends thereon, as shown at 6, 7, 8, 9 in Fig. 3, and the spools 10, 11, 12, 13 are built up as tube A revolves and as guide C reciprocates.

As the ends 6, 7, 8, 9 are not accurately placed, they as well as the tube, must generally be cut to form separate bobbins.

To support my cutting device, I prefer to use two brackets X and Y. Both are suitably bent and threaded whereby, as shown in Fig. 3, their ends 62 and 63 can be passed through holes or slots in the frame and the

brackets adjusted and fixed in position by nuts 64 and 65. The end 66 of Y is shown as in line with the pivot rod 40 forming the end of X and serving as a pivot and guide 5 for cutter carrier H.

My invention includes for each spindle, a cutter carrier H pivoted on 40 or on any suitable bracket attached to the frame and having arms 41 and 42 and a cutter shaft 43.

10 As shown in Figs. 1 to 3, I prefer to use disk cutters 44, 45, 46, loosely mounted between bushings 47 on shaft 43 in such positions as to enter between the bobbins which are to be formed and of such size that when 15 the cutters are swung forward past the tube A, they will cut into or score it, as shown in Fig. 6 but will not strike the metal spindle B.

The carrier H and cutters are so mounted 20 that they can swing past tube B and downward, as shown by the full lines in Fig. 2, to clear the built-up spools 10, 11, 12, 13 whereby they can be slipped off from the spindle when full.

25 To actuate the cutter carrier, I use a connecting rod 50 pivoted to carrier H at 51 and passing through a slot 35 in plate D. Rod 50 is shown as threaded to receive an adjusting nut 53 which regulates the distance 30 between guide C and the cutters for different sizes of spools. On the other side of plate D is a compression spring 54, the force of which is regulated by nuts 55. I prefer to use a fixed stop pin 70 on pivot 35 shaft 40 with which a slot 71 on carrier H engages to limit the downward movement thereof.

The parts are so adjusted that the cutters 40 will cut the tube sufficiently before the stop motion acts and I prefer to use disk cutters loosely mounted so that they will crawl and present new cutting edges to the tube.

As shown in Fig. 4, I may use knife cutters such as 60. In either case, as shown in 45 Fig. 6, I prefer to adjust the parts so that the tube A will not be cut entirely through but grooved or scored to a depth which is sufficient to allow the tube to be broken 50 apart. Such cutting, grooving or scoring also cuts the thread ends nearest the core in case they extend between the windings.

Adjusting nut 53 holds back the cutters and prevents them from prematurely cutting 55 the tube which might result in separating parts of the tube with their windings from the others. As the front end only is held by the expansion screw, such premature cutting would cause trouble.

60 On the other hand, if, as often happens, the spindle does not run true and begins to chatter, the follower spring 54 yields and allows the cutters to follow its movements without cutting the spindle or dulling the cutters.

Spring 54 also permits the cutters H to be dropped well down, as shown in Fig. 2, more readily than would a fixed pivot.

As the bracket rods X and Y can be adjusted in their respective slots and are preferably held by tightening nuts, the cutter carrier bearing shaft pivot can be moved with great freedom, while the adjusting nut 53 and tension nuts 55 allow the swing of the cutters and the tension thereon to be 75 changed for different sizes and types of work.

Usually several windings, such as the four shown, are made at the same time and, for proper operation of my automatic cutters 80 as well as to avoid waste, it is very necessary that a suitable thread guide, which will lay the thread evenly and will have no tendency to roll it off the ends, should be used.

I prefer to use, in connection with a guide 85 C having a plurality of thread guide slots 80 and round eyes 81 through which the thread passes from the tension rod 82, outlets formed with vertical V slots 83, as shown in Fig. 9, between which the material 90 at 84 is cut away, as shown clearly in Fig. 9, whereby the thread T passes out through sort of spouts 85, as shown clearly in Fig. 6, and no part of the guide actually touches either the tube A or the spool. 95

With this construction, there is no rubbing by the guide against the winding, which tends to cause the thread to fall over the ends, and the windings on all four spools are accurate and precisely the same so that 100 all are finished at the same time and, when the stop motion acts, all are cut to the same depth.

In operating the device after the stop motion acts, the operator takes hold of the 105 top of plate D, pulling it back and down to the position shown in Fig. 2. He then loosens the expansion screw 15, cuts the thread, removes the filled tube, tucks in the ends, places a new tube on the spindle, tightens the expansion screw, pushes up plate D and guide C to the spindle and starts the machine.

I claim:

1. The combination in a thread winding 115 machine having a frame, a revoluble spindle adapted to carry a paper tube, a thread guide carrier plate having a slot and adapted to move away from the tube as the thread is wound thereon, a reciprocating guide having guide eyes proximate such tube and carried by said plate, and mechanism operative by said plate for stopping such spindle when the tube has been wound to a predetermined point, with a cutter carrier 120 so pivoted to the frame that it can swing past the spindle, disk cutters loosely mounted thereon in such position that when the carrier is advanced they will cut such tube, a connecting rod attached to the cutter 125 130

carrier and extending through the guide carrier plate slot, a tension nut thereon, and a spring between such nut and the guide carrier plate.

- 5 2. The combination in a thread winding machine having a frame, a revoluble spindle adapted to carry a paper tube, a thread guide carrier plate adapted to move away from the tube as the thread is wound thereon, a reciprocating guide having guide eyes proximate such tube and carried by said plate, and mechanism operative by said plate for stopping such spindle when the tube has been wound to a predetermined 15 point, with a cutter carrier so pivoted to the frame that it can swing past the spindle, disk cutters loosely mounted thereon in such position that when the carrier is advanced they will cut such tube, together with a connecting rod so arranged as to connect such plate and the cutter carrier in such manner that the cutters will advance and cut the tube as the plate recedes, before the stop motion acts.
- 25 3. The combination in a thread winding machine having a frame, a revoluble spindle adapted to carry a paper tube, a thread guide carrier plate having a slot and adapted to move away from the tube as the thread is wound thereon, a reciprocating guide having a plurality of guide eyes proximate such tube and carried by said plate, and mechanism operative by said plate for stopping such spindle when the 30 tube has been wound to a predetermined point, with a cutter carrier so pivoted to the frame that it can swing past the spindle, disk cutters loosely mounted thereon in such position that when the carrier is advanced 35 they will cut such tube, a connecting rod attached to the cutter carrier and extending through the guide carrier plate slot, an adjusting nut on said rod between the guide plate and cutter carrier, a tension nut on said rod on the other side of the plate, and a follower spring between said tension nut and plate.
- 40 4. The combination in a thread winding machine having a revoluble spindle adapted 45 to carry a tube, a thread guide carrier plate
- adapted to move away from the tube as the thread is wound thereon, and a reciprocating thread guide having a plurality of thread guide outlets adjoining such spindle movable with said carrier plate, of cutters 55 so pivoted that when advanced they will cut such tube, together with connecting means between such plate and cutters including a follower spring whereby as the plate recedes the cutters advance. 60
5. The combination in a thread winding machine having a revoluble spindle adapted to carry a paper tube, and a thread guide carrier plate adapted to move away from the tube as the thread is wound thereon, of cutters 65 so pivoted that when advanced they will cut such tube, together with connecting means between such plate and cutters whereby as the plate recedes the cutters advance.
6. The combination in a winding machine 70 having a revoluble tube, and a plate adapted to move away from the tube as thread is wound thereon, of cutters so pivoted that when advanced they will cut such tube, together with connecting means between such 75 plate and cutters whereby as the plate recedes the cutters advance.
7. The combination in a thread winding machine having a revoluble spindle adapted to carry a tube, a thread guide carrier plate 80 having an opening and adapted to move away from the tube as the thread is wound thereon, and a thread guide having a thread guide outlet adjoining such spindle movable with said carrier plate, of a cutter carrier 85 so pivoted to the frame that it can swing up to the spindle, a cutter mounted thereon in such position that when the carrier is advanced it will cut such tube, a connecting rod attached to the cutter carrier 90 and extending through the opening in the guide carrier plate, an adjusting nut on said rod between the guide plate and cutter carrier, a tension nut on said rod on the other side of the plate, and a follower 95 spring between the said tension nut and plate.

In testimony whereof I have affixed my signature.

NAPOLEON RAIL.
